DISPENSING VALVE

Leonard M. Collins, Hollywood, Calif., assignor to Pressure Dispensers, Inc., Los Angeles, Calif., a corporation of California

Application May 13, 1957, Serial No. 658,820

23 Claims. (Cl. 222—525)

This invention relates generally to dispensing valves, and relates specifically to slidably opening and closing dispensing valves for use in connection with dispensing of liquids and powdery materials such as, for example, liquid and powder detergents.

In the past, liquid and powder detergents and the like have been dispensed from bottles and other containers having a pouring spout affixed to the container and having also a removable cover top which may be, for example, threaded onto the pouring spout. There are several disadvantages to the conventional method. The cover top, being removable, may be misplaced or dropped and broken by the user. Further, the use of pouring spouts generally requires that a relatively heavy material be used therefor contributing to the cost of manufacture and shipping.

Another disadvantage of the present conventional dispensing container is that the pouring spouts and the cover tops affixed thereto protrude from the container top a relatively great distance thus prohibiting ready stacking of the containers upon each other.

It is advantageous to use a slidably opening and closing valve that is at all times affixed to the dispensing container, thus eliminating the separable cover top and the heavy pouring spout, and which, in its closed position, protrudes but a short distance above the container top to enable ready stacking of a plurality of the containers.

Slidably opening and closing valves conventionally consist of a pair of telescoping members the outer member having one or more inlet ports communicating with the material to be dispensed, and the inner member having outlet ports. When the ports of each member are aligned, the liquid can then be dispensed. Registry means for insuring alignment of the ports of each member assumes a variety of forms; for example, the most common form for alignment of the ports incorporates a pin and slot arrangement preventing rotation of the telescoping members with respect to each other as they are slidably moved relative to each other. In this manner, the ports, upon movement of one member a predetermined distance, can always be placed in alignment. Such registry means add considerably to the cost of production and are not suitable, for example, where the valve is to be affixed to a throwaway dispensing container.

Another disadvantage of such conventional slidably opening and closing valves is that the necessary clearance between the telescoping members is a source of leakage of materials from the container.

Bearing in mind the foregoing facts, it is a major object of the present invention to provide a slidably opening and closing valve which is extremely simple in construction and inexpensive to manufacture, the valve construction eliminating the protruding neck, covering cap, and pouring spouts of conventional dispensing means, thereby enabling the stacking of a plurality of containers upon which the valve is mounted.

A further object of the present invention is to provide a slidably opening and closing valve comprising telescopic-

2

ing members having a simple and inexpensive construction wherein conventional means for registering inlet and outlet ports in each of the telescoping members is eliminated.

Still another object of the present invention is to provide a pair of telescoping members, which are readily assembleable to form a slidably open and closable two-position valve which, in its open position, regardless of the relative rotation of the telescoping members, has means for communicating the inlet and outlet ports of each member with each other, and which, in its closed position, regardless of the relative rotation of the telescoping members, positively prevents communication of these ports with each other.

Still a further object of the present invention is to provide a slidably opening and closing valve capable of ready assembly and having a pair of telescoping members which are substantially leak-proof when in closed position.

Yet another object of the present invention is to provide a dispensing valve comprising a pair of telescoping members wherein one of the members is slightly tapered, and the other is cylindrical to provide a sealing engagement between said members when said valve is in the closed position.

Still another object of the present invention is to provide means for readily affixing the dispensing valve to an opening in a dispensing container.

These and other objects of the present invention will become clearly understood by referring to the following description, and to the accompanying drawings, in which:

Figure 1 is a partially cut-away perspective view of a dispensing container showing one preferred form of my valve mounted therein, the valve being shown in its open position;

Figure 2 is a greatly enlarged axial cross-section of the valve shown in Figure 1;

Figure 3 is a greatly enlarged axial cross-section of the valve shown in Figure 1, the valve being shown in its closed position.

Figure 4 is a cross-section along the line 4—4 of Figure 2;

Figure 5 is a greatly enlarged axial cross-section of a modification of the valve shown in Figure 1, the valve being shown in full line in its open position and in dotted line in its closed position; and

Figure 6 is a cross-section along the line 6—6 of Figure 5.

Referring now to Figures 1 and 2, a preferred form of my dispensing valve 10 is shown mounted on the top end 12 of a dispensing container 14. The valve 10 consists of two telescoping sections including an outer sleeve 16, and an inner dispensing closure member 18 therein.

The sleeve 16 of the valve 10 has an axial bore 20 and a pair of transverse inlet ports 22 formed therein, the interior of the container 14 communicating with the sleeve bore by means of these transverse ports. The closure member 18 has an elongated stem 19 which is slidably received by the sleeve bore 20, the stem having formed therein a longitudinal axial outlet or dispensing passage 23 continuing upwardly through an enlarged head 32 to be described.

The passage 23 is adapted to communicate with the transverse inlet ports 22 of the sleeve 16 when the closure member 18 is suitably positioned. The communication means includes transverse passages 24 extending preferably radially from the longitudinal outlet passage 23 into an annular groove 25 formed within the outer wall of the stem 19 of the closure member 18, as best seen in Figures 2 and 4.

In order to suitably position the closure member 18

to assure communication of inlet ports 22 and the outlet passage 23 a stop member or flange 28 is preferably integrally affixed to the lower end of the stem 19 to limit the upward movement of the closure member. The flange 28 is enlarged with respect to the lower end of the stem 19, forming at the stem-flange juncture an annular shoulder 29 adapted to abut the lower end face 30 of the fixed sleeve 16 when the closure member 18 is moved to its uppermost position. As shown in Figures 2 and 4, upon abutment of shoulder 29 with end face 30, the annular groove 25 is in registry with the sleeve inlet ports 22.

It will be noted that the contents of the container 12 will be ejected either by gravity when the container is inverted, or by means of pressure applied to the container if the walls are pressure-deformable, through the sleeve inlet ports 22 into the annular groove 25; and the material will then move through the transverse passages 24 into the longitudinal dispensing passage 23.

It will be further noted that the transverse passages 24 need not be in alignment with the sleeve inlet ports 22, inasmuch as the material to be dispensed will always flow from the inlet ports into the annular groove 25, and thence into the transverse passages. Thus, regardless of the angular position of the closure member 18 with respect to the sleeve 16, means for communicating the inlet ports 22 and the outlet passage 23 are provided by merely moving the closure member 18 upwardly the maximum distance, as just described.

In order to insure a positive closure of the dispensing valve 10 upon simple downward movement of the closure member 18, the slidably stem 19 terminates in the enlarged head 32, previously mentioned, which is adapted to limit the downward movement of the stem. The fixed sleeve 16 terminates in an enlarged cap 34 and as the head 32 of the closure member 18 is slidably moved downwardly from the open position of Figure 2 to the position of Figure 3, the head abuts the cap to restrict further downward movement thereof. The amount of linear movement of the cap from its uppermost position (Figure 2) to its lowermost position (Figure 3) is such as to completely remove the annular groove 25 from communication with the inlet ports 22, as is clearly shown in Figure 3.

To further insure that the valve 10, in its closed position, is leak-proof, means are provided for positively preventing the entry of material from the container through the inlet ports 22, between the stem 19 and sleeve 16, and thence through the annular groove 25 to the dispensing passage 23. To this end, the sleeve 16 and closure member 18 are each made of a resiliently deformable material, such as, for example, polyethylene. As shown in Figure 2, the axial bore 20 of the sleeve 16 is formed with a tapered section 36 that progressively constricts the lower end of the bore. The upper section of the stem 19 in the region of the annular groove 25 is substantially cylindrical, the lower section 37 of the bore 20 being complementary to the tapered section 36, so that when the closure member 18 is moved downwardly to its lowermost position (Figure 3), it will exert an outward pressure upon the lower tapering wall of the bore section 36. Tight sealing engagement between the sleeve 16 and the stem 19 is thus provided in the region of the annular groove 25 so that the possibility of leakage through the inlet ports 22 to the annular groove is eliminated.

It will be seen that because the stem 19 is preferably pinched inwardly in its lower section 37 so that it may be easily slid upwardly through the pinched bore 36 to the open position of Figure 2.

The upper surface 38 of the sleeve cap 34 is slightly convex and the lower surface 40 of the head 32 is oppositely curved so that the thumb and finger may be

readily inserted between these surfaces to exert upward pressure upon the head thus readily opening the dispensing valve 10.

Attention is drawn to the fact that the sleeve cap 34 and the head 32 project only slightly above the top end 12 of the container 14 when the valve 10 is in closed position, so that the containers may be readily stacked with the valves mounted therein. The dispensing container 14 is provided with a slightly recessed bottom (not shown) to facilitate the nesting.

The resilient deformability of the sleeve 16 and the closure member 18 is also highly advantageous in effecting easy assembly of the valve 10 and for enabling ready assembly of the valve proper to the container 14 in a leak-proof manner.

In order to provide for easy assembly of the valve 10 the initial insertion of the closure member 18 within the sleeve 16 must be readily accomplished. To this end, the sleeve bore 20 is preferably made slightly downwardly tapering, the diameter of the upper end or mouth 42 of the bore 20 being substantially equal to the diameter of the stop member 28. As mentioned before, the lower section of the sleeve bore 20 is pinched inwardly in its lower section 36 for sealing purposes. However, the resilience of polyethylene, or many other plastic materials, is such as to readily permit complete passage of the stem 19 and the stop member 28 through the sleeve bore 20. Thereafter, the stem 19 and stop member 28 assume their original undistorted shape and size. Upon complete passage of the stop member 28 through the sleeve 16, the closure member 18 is then slidably from the open to the closed position, as previously described.

Once the valve 10 is assembled, it is readily mounted, so as to be leak-proof, in a circular opening 44 in the container top 12, in the following manner. The cap 34 comprises an upper lid 45 of greater diameter than the opening 44, and a cylindrical plug 46 of diameter substantially equal to the container opening 44. The side wall of the plug 46 has an annular bead 48 integrally formed thereon, the outer diameter of which is greater than that of the container opening 44.

The cap 34 of the assembled valve 10 is then forcibly inserted through the container top opening 44 so that the resilient bead 48 is compressed while passing therethrough. After passing therethrough, the bead 48 returns to its normal size and prevents movement of the sleeve 16, relative to the top end 12 of the container 14.

The bead 48 is spaced from the undersurface 52 of the lid 45 an axial distance substantially equal to, or slightly less than, the thickness of the container top 12 measured at the opening 44. The bead 48 and lid 45 are thus forced to tightly contact the edges of the opening 44 and prevent any leakage of material from the container 14.

Referring now to Figure 5, a modification of my dispensing valve is shown designated by numeral 10a and similarly comprises a resiliently deformable sleeve 16a press-fitted onto a container opening 44a, as previously described. The sleeve 16a has a resiliently deformable dispensing closure member 18a slidably movable therein and enclosed thereby.

As will be explained, the lower end 63 of the dispensing passage 60 of the closure member 18a is open and is adapted to be moved just above the sleeve inlet ports 22a. In this position, the inlet ports are placed in communication with the dispensing passage 60. It will thus be seen that the material from within the container 14 passes through the inlet ports 22a and thence directly into and through the dispensing passage 60 regardless of the circumferential positioning of the closure member 18a with respect to the fixed sleeve 16a.

The extent of upward movement of the closure member 18a necessary to insure appropriate communication is provided by an annular flange 64 preferably formed as a part of the closure member 18a intermediate its upper and lower ends 65, 63 respectively. The flange 64 rides

within an enlarged intermediate bore section 66 of main sleeve bore 20a and upon striking the upper annular shoulder 68, formed at the juncture between the enlarged bore 66 and the main bore 20a, prevents further upward movement of the closure member 18a. In this uppermost position of the closure member 18a, the lower open end 63 thereof lies in direct communication with ports 22a.

It will be seen that shoulder 68, in addition to limiting the upward movement of the closure member 18a also serves to retain the closure member within the sleeve 16a.

To close the valve 10a, the closure member 18a is slid downwardly within bore 20a until the head 32a of the closure member abuts the cap 34a, as shown by the dotted lines in Figure 5. The flange 64 then assumes a position intermediate the ends of the bore 66, also as shown in dotted line, and the lower end 63 of the closure member 18a is pressed against an annular sleeve seat 70. Any leakage of material from the container through the inlet ports 22a is prevented in a manner similar to that previously described with reference to valve 10. That is to say, the cylindrical stem 19a is slid downwardly into the sleeve bore 20a, which is tapered below the inlet ports 22a, to thus enable an exceedingly tight engagement to be made between the sleeve bore and closure member wall in the region of the inlet ports.

The assembly of the valve 10a is accomplished in much the same manner as is the valve 10. The stem 19a of the closure member 18a is slid downwardly within the sleeve bore 20a compressing the flange 64 and stretching the bore 20a considerably in order to permit the downward movement of the stem. The flange 64 assumes its normal size upon entering the bore 66 and rides therein within limits as previously described. Attention is also drawn to the wedge-shaped transverse cross-section of the flange 64 enabling the flange 64 to be more readily initially inserted within the mouth 42a of the bore 20a.

It is sometimes desirable to provide still additional sealing means as the closure member 18a is depressed to abut seat 70. To this end, an inner plug 74, circular in cross-section, is concentrically preferably integrally affixed to the valve seat 70 having a diameter at the base of the plug substantially equal to the bore 60 of the closure member 18a. The plug 74 is slightly tapered inwardly from the base thereof, as for example, assuming the general shape of a frustum of a cone to facilitate its entrance into the bore of the stem 19a. Thus, upon depression of the closure member 18a, the bore 60 is sealed by the inner plug 74, the plug 74 tightly interfitting the walls of the stem 19a, these walls being forced slightly outwardly, thereby against the bore 20a of the sleeve 16a, as described previously.

It will thus be seen that the combination of the inner plug 74 along with the means for providing tight engagement between the sleeve walls and the closure member 18a insure positive sealing engagement.

While several embodiments have been shown and described in some detail, it will be understood that substantial changes and modifications can be made that lie within the scope of my invention. For this reason, I do not intend to be limited to the embodiments herein shown and described, but only to the appended claims.

I claim:

1. A dispensing valve for a top opening container which comprises: a sleeve affixed to the opening of said container and having a bore formed therein; an inlet port forming a passageway between the interior of said container and said bore; a dispensing closure member slidably movable within said bore from a first position to a second position, and press-fitted within said bore for at least a portion of its travel in the region of said second position; a dispensing passage formed within said closure member and adapted to communicate with said inlet port when said closure member is in said first position, said inlet port being blocked when said closure member is in

said second position, said closure member being positively sealed within said bore when said closure member is in said second position to thereby prevent leakage of the material to be dispensed from within said container into said dispensing passage, by means of the press-fit of said bore and closure member in the region of said second position.

2. The dispensing valve defined in claim 1 wherein said dispensing closure member is composed of a head portion at its upper end and an elongated stem which is adapted to slidably move within said sleeve bore, said head portion protruding slightly above the top of said container when said valve is in closed position to thereby enable ready stacking of containers in which said valves are mounted.

3. A dispensing valve as defined in claim 1 having means for readily securing said closure member in said sleeve, said means comprising a flange affixed to said closure member of larger diameter than at least a portion of said sleeve bore and adapted to be forcibly inserted through at least a portion of said sleeve bore, the flange being adapted to abut a shoulder formed on said sleeve to prevent upward movement thereof.

4. A dispensing valve for a top opening container which comprises: a sleeve made of resiliently deformable material, affixed to the opening in said container and extending downwardly therefrom and having a bore formed therein, said sleeve having a portion thereof progressively constricted; at least one inlet port forming a passage between the interior of said container and said bore; a dispensing closure member having an elongated cylindrical stem slidable within said sleeve bore; and a dispensing passageway formed within said closure member and adapted to communicate with said inlet port when said closure member is in open position, said closure member being movable within said bore to a closed position to close said inlet ports, said cylindrical closure member in said closed position resiliently distending the walls of said constricted bore to thereby sealingly engage said closure member within said sleeve and positively prevent leakage of material from within said container through said inlet port.

5. A dispensing valve for a top opening container which comprises: a sleeve made of resiliently deformable material affixed to the opening in said container and extending downwardly therein, said sleeve having a bore formed therein, a portion of said bore being progressively constricted; an inlet port forming a passage between the interior of said container and said bore and formed above said constricted portion of said sleeve bore; a dispensing passageway formed within said closure member and adapted to communicate with said inlet port when said closure member is in open position; means for obtaining automatic communication between said dispensing passageway and said inlet port comprising movement-limiting means formed on said sleeve and on said closure member; and means for automatically obtaining a closure of said valve upon downward movement of said closure member which comprises downward-limiting means affixed to the walls of said bore and said sleeve, said closure member upon being moved downwardly within said bore, blocking said inlet ports and resiliently distending the constricted walls of said bore to thereby sealingly engage said closure member with the walls of said sleeve bore.

6. A dispensing valve for a container having an opening in one wall thereof, said wall having an outer surface and a lower surface, which comprises: a sleeve extending through said container opening having an upper thickened plug substantially equal to the diameter of said container opening, a resiliently deformable annular bead mounted on the periphery of said plug, a lid of larger diameter than said plug and spaced from said bead and adapted to overlap the upper edges of said container opening, the spacing between said lid and bead being

slightly less than the thickness of said container wall at the opening thereof whereby said sleeve is adapted to be press-fitted on said container by forcing said plug through said container opening until said lid abuts the outer surface of said container wall and until said bead abuts the lower surface of said container wall, the sleeve being thereby mounted onto said container in a leak-proof manner and having formed therein, a bore; an inlet port communicating the interior of said container with said bore; a dispensing closure member slidably movable within said bore from an open position to a closed position; a dispensing passageway formed within said closure member and adapted to communicate with said inlet port when said closure member is in an open position, said inlet port being blocked when said closure member is in said closed position; and means for positively sealing said closure member within said bore when said closure member is in said closed position so as to prevent leakage of materials from within the container through said inlet port.

7. A dispensing valve for a container having an opening therein which comprises: a sleeve affixed to the opening in the top of said container and extending downwardly therein, said sleeve having a bore formed therein; an inlet port forming a passage between the interior of said container and said bore; a dispensing closure member having an outer wall slidably movable within said bore from an open position to a closed position, said bore having a smaller diameter than said closure member at the region in said bore corresponding to the closed position of said closure member; a longitudinal dispensing passage formed within said closure member; an annular groove formed within the outer wall of said closure member and communicating with said longitudinal dispensing passage by a passageway, said inlet port being adapted to communicate with said annular groove when said closure member is in an open position, and being blocked by the outer wall of said closure member when said closure member is in its closed position, said bore being of smaller diameter than said closure member at the region in said bore corresponding to the closed position of said closure member, providing thereby means for positively sealing said closure member within said bore so as to prevent leakage of material from said container through said inlet port into said dispensing passageway.

8. A dispensing valve for a container having an opening, which comprises: a sleeve, made of resiliently deformable material, affixed to the opening of the top of said container and extending downwardly therein, said sleeve having a bore formed therein which is constricted in its lower section; at least one inlet port forming a passage between the interior of said container and said bore and being positioned above said constricted section; a dispensing closure member having an elongated cylindrical stem slidable within said sleeve bore and terminating in an upper enlarged head; a longitudinal dispensing passage formed within said elongated stem of said closure member and extending through said enlarged head; and an annular groove formed within the periphery of said closure member; means for communicating said annular groove with said dispensing passage, said annular groove being adapted to communicate with said inlet ports when said closure member moves slidably upwardly to a predetermined position, said inlet ports being blocked by the walls of said closure member when said closure member is slid downwardly to a predetermined position wherein said cylindrical stem distends said tapered bore and positively seals said closure member within said bore, to thereby prevent leakage of materials from said container through said inlet ports.

9. The apparatus of claim 8 wherein the container opening is defined by a sidewall having an outer edge and an inner edge, said sleeve has an upper thickened plug substantially equal to the diameter of said container opening, a resiliently deformable annular bead is mount-

ed on the periphery of said flange, a lid of larger diameter than said plug is spaced from said bead and is adapted to overlap the edges of said container opening, the spacing between said lid and bead being substantially equal to the thickness of said sidewall opening whereby said sleeve is adapted to be press-fitted onto said container by forcing said sleeve through said container opening until said lid abuts the outer edge of said sidewall and until said bead abuts the inner edge of said sidewall to thereby mount the dispensing valve to the container in a leak-proof manner.

10. The apparatus of claim 8 characterized in that said dispensing closure member has an enlarged lower end whereby when said closure member is slid upwardly, said enlarged lower end abuts the sleeve to prevent further movement, whereby communication between the annular groove and the inlet port of the sleeve is automatically obtained, said sleeve having means thereon to prohibit downward movement of said closure member past a predetermined point whereby, when said closure member is moved downwardly this maximum distance, said annular groove and said inlet port are positively not in communication.

11. A dispensing valve as defined in claim 8 having means for readily securing said closure member in said sleeve, said means comprising a resiliently deformable flange affixed to said closure member of larger diameter than the lower portion of said sleeve bore and adapted to be compressed inwardly as said closure member is forced downwardly through said sleeve bore, the flange being adapted to abut the lower edge of said sleeve bore to prevent upward movement thereof.

12. A dispensing valve for a top-open container which comprises: a sleeve affixed to the opening in the top of said container and extending downwardly therein; a bore formed within said sleeve and terminating above the bottom of said sleeve; at least one inlet port forming a passage between the interior of said container and said bore; a dispensing closure member having an outer wall, slidably movable within said sleeve bore from a first position to a second position; a dispensing passage formed within said closure member and passing completely therethrough and adapted to communicate with said inlet port when said closure member is in said first position, said inlet port being blocked by the outer wall of said closure member when said closure member is in its second position, the portion of said outer wall of said closure member, in the region of said inlet port, being press-fitted within said sleeve bore, thereby positively sealing said closure member within said sleeve bore when in said second closed position so as to prevent leakage of material within the container through said inlet port.

13. A dispensing valve for a top opening container which comprises: a sleeve made of resiliently deformable material affixed to the opening of said container and extending downwardly therein; a bore formed within said sleeve and terminating above the lower edge thereof; at least one inlet port communicating the interior of said container with said sleeve bore, said bore having a constricted section in the region of said inlet port; a dispensing closure member made of a resiliently deformable material and having an elongated cylindrical stem slidable within said sleeve bore, and having an upper enlarged head affixed to said cylindrical stem; and a dispensing passage formed within said closure member passing completely therethrough along the longitudinal axis thereof, said valve having upper movement-limiting means whereby said closure member is slid upwardly within said sleeve bore a predetermined distance whereby said lower end of said closure member bore communicates with said inlet ports, said valve having downward movement-limiting means comprising the abutment of said enlarged head portion of said closure member with said sleeve, the positioning of said closure member in its most downward position being such that the walls of said

closure member block said inlet port, and said tapering bore of said sleeve member is distended by downward movement of said cylindrical closure member to thereby positively prevent leakage of material from said container through said inlet ports and into said dispensing passage.

14. A dispensing valve for a top-open container comprising: a sleeve affixed to the opening in the top of said container and extending downwardly therein, the opening in said top being defined by a side wall having an upper edge and a lower edge; a bore formed within said sleeve and terminating above the bottom of said sleeve, said sleeve having an upper thickened plug substantially equal in diameter to the diameter of said container opening; a resiliently deformable annular bead on the periphery of said plug; a lid of larger diameter than said plug spaced from said bead and adapted to overlap the upper edge of said container opening, the longitudinal distance between said lid and bead being substantially equal to the axial thickness of said side wall opening whereby said sleeve is adapted to be press-fitted, in a leak-proof manner, into said container by forcing said sleeve through said container opening until said lid abuts the upper surface of said container top and until said bead abuts the lower edge of said container opening; an inlet port in said sleeve forming a passage between the interior of said container and said bore; a dispensing closure member slidably movable within said sleeve bore from a first position to a second position; a dispensing passage formed within said closure member and passing completely therethrough and adapted to communicate with said inlet port when said closure member is in said first position, said inlet port being blocked by the wall of said closure member when said closure member is in its second position; and means for positively sealing said closure member within said bore when in said second closed position so as to prevent leakage of material within the container through said inlet port.

15. A dispensing valve for a container having a circular top opening which comprises: a sleeve affixed to the opening in the top of said container and extending downwardly therein; a bore formed within said sleeve and terminating above the bottom of said sleeve; an inlet port forming a passage between the interior of said container and said bore; a dispensing closure member slidably movable within said sleeve bore from a first position to a second position; means for readily securing said closure member in said sleeve, said means comprising a resiliently deformable flange affixed to said closure member of larger diameter than the upper portion of said sleeve bore and adapted to be compressed inwardly as said closure member is forced downwardly through said upper portion of said sleeve bore, said flange expanding into a second enlarged portion of said sleeve bore to its normal diameter, the flange being adapted to abut a shoulder formed between said bores to prevent upward movement thereof; a dispensing passage formed within said closure member and passing completely therethrough and adapted to communicate with said inlet port when said closure member is in said first position, said inlet port being blocked by the wall of said closure member when said closure member is in its second position; and means for positively sealing said closure member within said bore when in said second closed position so as to prevent leakage of material within the container through said inlet port.

16. A dispensing valve for a top-open container which comprises: a sleeve affixed to the opening in the top of said container and extending downwardly therein; a bore formed within said sleeve and terminating above the bottom of said sleeve; an inlet port forming a passage between the interior of said container and said bore; a dispensing closure member slidably movable within said sleeve bore from a first position to a second position; a dispensing passage formed within said closure member

and passing completely therethrough and adapted to communicate with said inlet ports when said closure member is in said first position, said inlet ports being blocked by the wall of said closure member when said closure member is in its second position; means for positively sealing said closure member within said bore when in said second closed position so as to prevent leakage of material within the container through said inlet port; means limiting the downward movement of said closure member to positively prevent communication between said inlet port and said dispensing passage; and means limiting the upward movement of said closure member insuring communication of said inlet port and said dispensing passage.

17. Apparatus according to claim 16 wherein the closure member has an enlarged head mounted at the upper end thereof and a spaced peripheral flange affixed thereto, said head and flange each coating with stop means on said sleeve to limit the downward and upward movement respectively of said closure member relative to said sleeve.

18. Apparatus according to claim 16 wherein the closure member has a peripheral flange affixed to the outer wall thereof, said flange coating with said sleeve to limit the movement of said closure member relative to said sleeve.

19. A dispensing valve for a container having a circular top opening which comprises: a sleeve affixed to the opening in the top of said container and having a bore formed therein; an inlet port forming a passageway between the interior of said container and said bore; a dispensing closure member slidably movable within said bore from a first position to a second position; a dispensing passage formed within said closure member and having an inlet end adapted to communicate with said inlet port when said closure member is in said first position, said inlet port being blocked when said closure member is in said second position; and means for positively sealing said closure member within said bore when said closure member is in said closed position to thereby prevent leakage of the material to be dispensed from within said container, said sealing means including a resilient plug having a portion of slightly larger diameter than the diameter of said dispensing passage, said plug being adapted to be press-fitted into the inlet end of said passage.

20. The valve of claim 1 wherein a plug is affixed to said sleeve, said plug having a portion of slightly larger diameter than the diameter of said dispensing passage, said plug being adapted to be press-fitted into the inlet end of said passage.

21. The dispensing valve according to claim 1 wherein a plug is affixed to said sleeve, said plug progressively increasing in diameter until the largest diameter thereof is slightly larger than the diameter of said dispensing passage, said plug being adapted to be press-fitted into the inlet end of said passage.

22. The dispensing valve of claim 12 wherein a plug is formed on the bottom of said bore, said plug having a portion of slightly larger diameter than the diameter of said dispensing passage.

23. The dispensing valve as defined in claim 12 wherein a resilient plug is formed on the bottom of said bore, said plug progressively increasing in diameter until the largest diameter thereof is slightly larger than the diameter of said dispensing passage, said plug being adapted to be press-fitted into the inlet end of said passage.
